ROBERT ABSALOM THOM, OF MANCHESTER, ENGLAND, AND JAMES THOM, OF ABERDEEN, SCOTLAND.

STEAM GENERATOR.

Application filed December 13, 1923, Serial No. 680,510, and in Great Britain April 10, 1923.

This invention has reference to steam generators and principally to steam generators of the water-tube type; the invention also relates to an improved water-tube equipment for the fire-boxes or furnace chambers of railway locomotive and other boilers or steam generators.

While the invention has been designed primarily for use as or in conjunction with a railway locomotive boiler the invention is not restricted to such boilers but is also applicable to steam generators or boilers of other types and for various purposes; for instance the invention is applicable to marine boilers, road locomotive boilers, stationary boilers, portable engine boilers (for instance boilers or steam generators for operating the pumps of fire-engines), and to boilers or steam generators for operating air-craft propulsion engines.

The principal objects of the invention are to provide an improved construction of water-tube boiler or water-tube fire-box equipment whereby more effective and rapid heating of the water is obtained and generation of steam accelerated, the tubes forming the side walls of the fire-box being so formed and arranged as to permit expansion and contraction without strain and consequent damage to the joints of the said water tubes to the headers, distributors or collectors, and generally to improve the construction as a whole in order to provide simplicity, compactness and durability. In a boiler according to this invention the several water distributors or collectors are of simple construction and are also such that the water tubes connected thereto may be easily expanded into the holes provided to receive them, the distributors and collectors being also such as to provide the necessary strength to withstand high working pressures without being unduly heavy or cumbersome. An important object of the present invention is to produce or provide a steam generator which while being of minimum weight shall have a very high, or the maximum, steaming capacity.

In the case of a railway locomotive boiler with water-tube fire-box equipment according to this invention the construction and arrangement of the parts are such that the usual external configuration and dimensions

of the boiler barrel and fire-box shell or casing can be maintained, the construction and arrangements being also such that the usual crown and side stays of the fire-box are eliminated; further the back plate of the boiler at the driver's cab can have the same profile as in a boiler of the present usual construction in which the fire-box has side water spaces or chambers, so that the usual steam fittings on the back plate can be placed in the positions they usually occupy in the boilers now generally in use.

A water-tube boiler or a water-tube fire-box equipment according to this invention comprises, in combination, a water distributor or water distributing chamber arranged in communication with a water supply vessel or chamber which, in the case of a locomotive type boiler, may be the water space in the boiler barrel, and preferably (in the case of a locomotive type boiler) also in communication with the water space between the inner and outer plates or walls at the fire-door or fire-hole end of the fire-box, or furnace chamber, a header or junction box or headers or junction boxes or the equivalent preferably located at or near the bottom of the fire-box or furnace chamber, a water collector or water receiving drum or drums preferably situated at a level above the said water distributor or distributors, a plurality of downflow tubes situated at or adjacent each side of the fire-box or furnace chamber and connecting the aforesaid water distributor or distributors with the aforesaid header or headers or junction boxes, and a plurality of similarly situated up-flow tubes connecting the said headers or junction boxes with the aforesaid drum or drums. The said water collector or receiving drum or drums is or are preferably arranged in communication, for instance, at one end, with the steam and water space of the boiler and also in communication, for instance at the opposite end, with the corresponding space between the inner and outer plates or walls at the fire-door or fire-hole end of the fire-box or furnace chamber.

Further according to this invention, in the preferred embodiment, the aforesaid down-flow-water tubes are arranged as an outer row of vertically disposed tubes adjacent the plates constituting the side walls (ordi-

narily the shell or envelope) of the fire-box or furnace chamber, each of the said down-flow tubes being of a suitably larger diameter or cross area than that of the aforesaid 5 up-flow tubes which are arranged as an inner row or rows of vertically disposed tubes, the said inner and outer rows of tubes at each side of the fire-box thus constituting the side walls of the fire-space within the 10 fire-box, and the said rows of tubes and the aforesaid water distributors and headers or junction boxes being located or accommodated in spaces corresponding or approximately corresponding to the usual water 15 spaces at each side of an ordinary fire-box of a locomotive boiler.

A further feature of the water-tube boiler or fire-box equipment according to this invention consists in the aforesaid downflow 20 tubes being of oval, elliptical or suitably flattened form in cross-section, whereby while obtaining the relatively large diameter or cross area of these tubes they and their associated up-flow tubes occupy a minimum 25 space in the lateral or transverse direction, and form a practically continuous water jacket at each side of the furnace chamber or fire space in the fire-box. Further the construction and arrangements are such that 30 in a space, for instance a fire-box, of given dimensions a relatively large or the maximum number of water-tubes comprising down-flow and up-flow tubes can be accommodated and further can be accommodated 35 in the small space available at each side of the fire-box of a locomotive or other boiler.

The invention further consists in the combination of the various devices or parts 40 constituting the water-tube boiler and its arrangement in the fire-box of a locomotive boiler, and in constructional details of certain of the said devices or parts substantially as hereinafter described with reference to the accompanying drawings and set forth 45 in the appended claims.

In the accompanying drawings:—

Fig. 1 is a longitudinal vertical section of the fire-box and a portion of the boiler barrel of a locomotive boiler of the smoke or fire-tube type with water-tube boiler 50 equipment according to one embodiment of this invention applied thereto.

Fig. 2 is a cross-section, taken on the line 2—2 in Fig. 1, and looking from the right hand. Fig. 2^a is a cross-section, taken on the line 2^a—2^a in Fig. 1, and looking from the left hand. Fig. 3 is a sectional plan view, taken on the line 3—3 in Fig. 1.

Fig. 3^a is a sectional plan view, taken on the line 3^a—3^a in Fig. 2^a.

Figs. 4—17 are detail views showing the construction of certain parts of the fire-box water-tube equipment shown in Figs. 1 and 2 and hereinafter described. Fig. 17^a is 65 a broken longitudinal section through one of

the water distributors 9 showing its communication with the water spaces at the ends of the fire-box casing. Fig. 17^b is a section on one end portion of the water receiving drum 8 showing it welded in a hole in the 70 end plate, and is drawn to a larger scale.

Figs. 18 and 19 are respectively front and side sectional elevations of portions of a locomotive fire-box showing a modified construction hereinafter described. 75

Fig. 20 is a detail view showing a form or method of construction of the water distributors employed in the construction shown in Figs. 18 and 19.

Fig. 21 is a view similar to Fig. 1, but shows a modification. Fig. 22 is a view similar to Fig. 2, and Fig. 22^a is a view similar to Fig. 2^a, also showing the said modification. 80

Figs. 23 and 24 are detail views, respectively a sectional plan and a transverse section, of one of the headers or junction boxes shown in Figs. 21 and 22 but drawn to a larger scale. 85

Fig. 25 is a sectional elevation of portion 90 of a fire-box showing a modified construction hereinafter described.

Like reference numbers indicate like parts in the various figures of the drawings.

In the drawings, 1 is a portion of the barrel of a locomotive boiler of the usual smoke or fire-tube type, 2 being the boiler tube-plate at the fire-box end of the barrel and 3, 3^a the smoke-tubes of the boiler, the smoke-tubes 3^a being the usual enlarged smoke-tubes 100 into which U-shaped superheating pipes or steam superheater elements (not shown) extend. 4 is the back plate of the boiler at the rear or fire-door end of the fire-box, 5 and 5^a respectively the rear and front end 105 plates of the fire-box, and 6 are the plates forming the sides and top of the fire-box casing or shell. 4^a is the front end plate of the fire-box casing. The fire-box tube-plate 2 as shown is a flanged or dished 110 plate, the flanged portion of which is let into and secured to the forwardly projecting or flanged portion 5^b of the inner plate 5^a at the front end of the fire-box. Apertures 7 and 7^a are formed respectively in the plate 5 at the rear end of the fire-box and in the inner plate 5^a at the front end 115 of the fire-box, the inwardly turned portions or flanges 7^b, 7^c of the said plates surrounding the said apertures and constituting sockets which receive the ends of the hereinbefore mentioned water receiving drum or water collector 8 which in the example shown is cylindrical in cross-section, its ends being secured, for instance by riveting, to the 120 flanges 7^b, 7^c.

As will be understood the usual inner side plates or side walls and crown plates of the fire-box or furnace chamber proper as employed in the usual fire-boxes of loco- 130

motive boilers are omitted from a fire-box to which a water-tube boiler equipment, according to this invention, is applied.

9 are the hereinbefore mentioned water 5 distributors situated adjacent to the plates 6 at opposite sides of the fire-box. These water distributors have the form of open-ended boxes of oblong or approximately rectangular form in cross section, and are, 10 through their open ends, in free communication with the water space of the boiler their rear ends communicating with the water space between the plates 4 and 5, apertures being provided in the plate 5 at the rear 15 end of the firebox and in the inner plate 5^a at the front end of the fire-box with which apertures the open ends of the said water distributors register. 10 are flanges provided on the ends of the water distributors 20 9 whereby they are secured respectively to the plate 5 at the rear end of the fire-box and to the inner plate 5^a at the front end of the fire-box, for instance, as shown, by being riveted to the said plates.

25 11 are the hereinbefore mentioned headers or junction boxes situated at or adjacent to the bottom of the fire-box or furnace chamber and extending from front to rear thereof as shown in Figs. 1 and 2. 12 are the hereinbefore mentioned down-flow or down-take water tubes of relatively large diameter or cross area, and 13 are the up-flow tubes of relatively small diameter or cross area. As will be clearly seen in Figs. 2 and 3 of 30 the drawings the down-flow tubes 12 are arranged as an outer row of tubes adjacent to the side plates or wall 6 of the fire-box and the up-flow tubes 13 are arranged as an inner row of tubes, the upper portions of these tubes, in the example shown, being bent to conform approximately to the cross-sectional contour of the fire-box walls or shell 6. The upper or inlet ends of the down-flow tubes 12, are, as shown, secured (in this instance expanded in holes) in the 35 bottom of the water distributors 9, 14 being screw plugs in holes in the top of these distributors for the insertion of a tube expanding tool. The lower or outlet ends of the said down-flow tubes 12 are secured (in this instance expanded in holes) in the top of the aforesaid headers or junction boxes 11, openings 11^a being provided in the bottom 40 of the header 11 for the insertion of the tube expanding tool and cover plates 15 provided for closing the said openings these cover plates being secured to the bottom of the headers 11 by means of studs and nuts or otherwise as may be found practicable. The 45 lower or inlet ends of the up-flow tubes 13 are also, as shown, expanded in holes in the top of the headers or junction boxes 11 and the upper or outlet ends of the said tubes 13 are secured (in this instance expanded) 50 in holes in the hereinbefore mentioned water

receiving drum or water collector 8. As will be seen the up-flow tubes 13 in each row of these tubes are arranged as close together as practicable and in such manner in relation to the associated down-flow tubes 12, constituting the outer row, that opposite the space between adjacent tubes 12 there is a tube 13 the arrangement being therefore such that the associated rows of inner and outer water tubes 12, 13, form practically continuous side walls of the fire-box or furnace chamber proper, very little lagging being required in the spaces between the rows of tubes 12 and the side plates 6 forming the shell or outer wall of the fire-box. 70 Further the inwardly bent upper portions 13^a of the closely spaced water-tubes 13, together with wrapper plates 16, located above these bent portions, and the lower portion of the drum 8 constitute the crown or top of 80 the fire-box or furnace chamber proper. As shown the wrapper plates 16 extend from the water receiving drum 8 to the water distributors 9 and are secured (for instance riveted) to brackets 17, 17^a fixed respectively 90 to the side of the drum 8 and to the side of the water distributors 9.

According to this invention in the preferred embodiment thereof the aforesaid down-take or down-flow water tubes 12 are 95 of oval, elliptical or flattened form in cross-section, as shown in Figs. 14, 15, 16 and 17 of the drawings, with circular end portions 12^a, 12^b whereby the said tubes are expanded in the water distributors 9 and headers or junction boxes 11 as hereinbefore described. This form or construction of the tubes 12 enables ample bridge spaces to be provided between the holes in the water distributors 9 and in the junction boxes 11 in which the 100 ends 12^a, 12^b of the said tubes are expanded, while at the same time providing the necessary relatively large cross area of the tubes 12 and enabling these tubes and the tubes 13 of the inner row at each side of the fire-box 105 to be accommodated in the same or approximately the same restricted space as that which constitutes the usual water space between the outer plate 6 or shell of the fire-box and the inner plate or side walls of the 110 fire-box or furnace chamber proper as provided in the usual fire-box of an ordinary locomotive boiler.

The aforesaid tubes 12 of oval, elliptical or flattened cross-section can be conveniently produced from solid drawn steel tubes of circular cross-section by taking a tube of larger diameter than that desired for the end portions 12^a, 12^b and swaging down the ends of said tube to the desired diameter 120 for connection to the junction boxes 11 and water distributors 9, and by then pressing down or flattening the main length of the tube between the swaged down ends 12^a, 12^b 125 until the dimension of the tube in one direc- 130

tion of its cross section corresponds to the diameter of the said swaged down ends, the dimension of the tube in the other direction of its cross-section being considerably increased, and approximately equal to the distance between centers of the tube holes 20 in the bottom of the water distributors or feeders 9 and also approximately equal to the distance between centers of the tube holes 21 in the top of the junction boxes 11, the tube being thereafter bent to the shape required, so that when in place the upper end portions of the tubes are set outwardly to conform or substantially conform to the shape of the shell or outer plate structure of the fire-box.

The hereinbefore mentioned water distributors 9 may each be conveniently formed of two pressings welded or otherwise suitably secured together. Referring to Figs. 4 and 5 of the drawings, in one method of constructing the water distributors 9 portions of steel plate each of the required dimensions to form one-half of the distributor are first 25 pressed into a U or channel shape (see Fig. 4) and the end portions thereof are subsequently flanged in a suitable flanging press, to produce the flanges 10. The meeting edges of the sides of the two U-shape 30 portions or halves of the distributor are suitably chamfered or otherwise machined to provide a satisfactory bed for the metal deposited in the operation of welding the two U-shaped pressings together.

35 The junction boxes or headers 11 may be formed by pressing operations on a metal plate. In one method of producing such a junction box or header a flat metal plate of required dimension is first pressed into 40 channel form (see Fig. 6 of the drawings) and then by a further pressing operation or operations the sides or walls of the channel are bent inwardly until they meet (see Fig. 45 of the drawings) so as to form a tube or box of suitable cross-section; the meeting edges of the plate are preferably chamfered to form a bed for the metal deposited in the welding operation whereby the edges of the plate are secured together, 11^b (Fig. 7) 50 indicating the welding metal by which the said edges are united. The ends of the tube or box thus produced are then closed by end plates 11^c welded in place as shown in Fig. 8. In the top or upper wall of the junction box thus produced the necessary holes to receive the ends of the down-flow and up-flow water circulating tubes 12 and 13 are formed, and the hereinbefore mentioned openings 11^a (Figs. 2 and 9) are 55 formed in the bottom or lower wall of the junction box. In the preferred construction of the junction box as above described the welded or meeting edges of the metal of which the box is formed are arranged or 60 located in the wall of the box in which the

aforesaid relatively large openings 11^a are provided so that it is only necessary to connect or weld together the edges of those portions of the metal plates which lie between or form transverse bars or bridges 70 between the ends of adjacent openings 11^a. In these bars or bridges holes or openings closed by screw plugs are formed to permit the entrance of a tube expander for securing the ends of such of the water tubes 13 75 as lie opposite the said transverse bars or bridges, these holes being indicated by the reference numerals 18 in Fig. 9 of the drawings. Around the openings 11^a in the bottom of the junction box are screw studs 19 80 (Fig. 9), whereby the cover plates 15 are secured in place so as to close the openings 11^a.

20 and 21 (Figs. 3) are the holes respectively in the bottom of the water distributor 9 and in the top of the header or junction box 11 in which the ends 12^a and 12^b respectively of the down-flow water tubes 12 are expanded, and 22, 22^a are the holes in the top of the header or junction box 11 85 in which the lower or inlet ends of the up-flow water-tube 13 are expanded. In order to provide adequate bridges between the holes 22, 22^a in the top of the junction box 11 these holes are arranged in two parallel 90 rows the holes 22^a in the outer row being located opposite the bridges or portions of metal between the holes 22 in the inner row and also located opposite the bridges 95 or portions of metal between the holes 21 100 in which the ends 12^b of the down-flow tubes 12 are expanded. The said up-flow tubes 13 secured in the holes 22, 22^a are, at a short distance above the top of the junction box 11, so bent that they lie in a vertical 105 plane intermediate the planes in which the two rows of holes lie, the tubes secured in the holes 22 being bent outwardly towards the plates 6 forming the side or shell of the fire-box, and the tubes secured in the holes 22^a bent inwardly towards the center of the fire-box, the tubes secured in the holes 22 being also bent in a longitudinal plane 110 of the fire-box so that the main portion of all the up-flow tubes 13 (i. e. those secured in the hole 22 and those secured in the hole 22^a) lie in the same longitudinal plane of the fire-box and are evenly spaced apart.

115 In the alternative construction illustrated in Figs. 18, 19 and 20 of the drawing parts corresponding to those above described with reference to and shown in Figs. 1 to 17 of the drawings are indicated by the same reference numbers as are applied to the parts in Figs. 1 to 17. In the alternative constructions shown in Figs. 18, 19, instead of the water distributors 9 being made of two U-shaped pressings welded together as hereinbefore described with reference to Figs. 4 120 and 5 of the drawings, these distributors are 125 130

each made from a single piece of metal plate pressed or bent to form a tubular structure or open-ended box as shown in Fig. 20 in which the opposite edges of the bent metal plate are welded together at 11^a. Further these water distributors 9 and the cylindrical water collector or water receiving drum 8 are secured to the plate 5 at the rear of the fire-box and to the inner plate 5^a at the front 10 of the fire-box by welding, the inturned flanges 7^b, 7^c (Fig. 1) surrounding the apertures in the said plates being omitted in the construction illustrated in Figs. 18 and 19.

As shown in Fig. 17^b the drum 8 is machined or turned down at each end to provide a slight shoulder 8^a which lies at the inner edge of the aperture in the tube-plate 2^a at the front end of the fire-box, the hereinbefore described dished or flanged plate 2 20 employed in the construction illustrated in Fig. 1 being omitted. As shown in Fig. 19 the turned down or reduced end of the drum 8 projects slightly beyond the tube-plate 2^a. Similarly the ends of each of the water 25 distributors 9 are, as shown in Fig. 19, machined or turned down so as to provide a slight shoulder, the shoulder 9^a at one end of the distributor lying at the inner edge of the aperture in the said plate 2^a and the corresponding shoulder of the opposite end lying at the inner edge of the corresponding aperture in the plate 5 (Fig. 1) at the rear or fire hole end of the fire-box.

In assembling the various parts of the 35 water-tube boiler equipment in the fire-box when employing water distributors 9 constructed in the manner described with reference to Figs. 18, 19 and 20 of the drawings, these distributors are preferably so arranged 40 that the welded joint 11^a (Fig. 20) is adjacent to the plates 6 constituting the shell or side walls of the fire-box.

As shown in Figs. 1 and 18 the water 45 distributors 9 are provided with a suitable number of transverse stays 23 these stays being arranged so as to lie directly above the bridges between the ends of the down-flow tubes 12 secured in the bottom of the distributors.

Referring now to Figs. 21, 22, 23 and 24 of the drawings, which illustrate a modified construction of the water-tube boiler or water-tube equipment suitable either for a locomotive boiler or a marine boiler and also suitable for use as either a stationary or a portable boiler or steam generator, the differences between the constructions shown in these figures and the constructions hereinbefore described with reference to Figs. 1 to 20 of the drawings will be apparent but may be briefly described as follows:—

The headers or junction boxes 11 in the upper wall of which the lower ends of the hereinbefore mentioned downtake or down-flow tubes 12 and uptake or up-flow tubes 13

are fixed are in this instance each provided with covers 15^a of dish or channel form in cross-section in the sloping ends of which covers screw plugs 15^b (Fig. 21) are provided whereby sediment, sludge or matter 70 carried down in the water and deposited in the said junction boxes will settle in the recesses formed in the dish-shape covers 15^a and can be readily cleared out by removing the screw plugs 15^b and inserting the nozzle 75 of a water hose in the plug hole. Further, as will be seen on reference to Fig. 23, the arrangement of the ends of the water uptake or up-flow tubes 13 in the top of the junction box differs from that shown in 80 Fig. 3, and a larger number of these tubes 13 is provided, there being, as shown in Fig. 23, six of these uptake tubes 13 to each downtake tube 12 so that in this case the heating surface is largely increased as compared with that of the construction illustrated in Figs. 1, 2 and 3. Further as shown in Fig. 21 the hereinbefore mentioned dished or flanged tube-plate 2 is in this case 85 secured in the forward end of a tubular and more or less tapering extension or chamber 24 the rear end of which is secured in the flange portion 5^b of the inner plate 5^a at the front end of the fire-box. The water distributors 9 in Figs. 21 and 22 may each be 90 made from a single piece of plate metal bent and welded as hereinbefore described with reference to Fig. 20; further, instead of holes closed by screw plugs, as shown in Fig. 18 of the drawings, being provided in 100 the top of the water distributor shown in Fig. 22 relatively large openings may be formed in the top of each distributor and closed by cover plates 14^a which may be secured to the top of the distributor by 105 screw studs and nuts.

Referring to Fig. 25 which illustrates a modified construction of the fire-box casting or shell, in this case it will be seen that the rear end plate 5 of the fire-box, instead of extending to the bottom of the fire-box as in the constructions shown in Figs. 1 and 2, terminates at a position above the fire-hole or fire-door opening 30 and below the bottom of the water distributor 9 which is arranged at a higher level in the fire-box than are the distributors 9 shown in Figs. 1 and 21. Similarly the inner plate 5^a at the front end of the fire-box in Fig. 25 terminates at a position a short distance below the level of the bottom of the boiler barrel instead of, as in Figs. 1 and 21, extending to the bottom of the fire-box. 31 and 32 are fire-brick linings respectively at the inside of the back plate 4 at the rear of the fire-box and at the inside of the outer plate 5^a at the front end of the fire-box. The construction shown in Fig. 25 and above described is particularly suitable for marine, stationary and portable boilers.

In Figs. 2 and 3, 25 is a strengthening or stiffening plate of approximately U-shape in cross-section, the said plate being secured, for instance riveted, to the back-plate 4; as shown this plate 25 extends a short distance into the adjacent end of the water distributor 9. That portion of the plate 25 which lies in the water space between the back plate 4 and the plate 5, as shown in the right-hand portion of Fig. 2, is of greater depth or height than the portion which extends into the water distributor 9 so that within the said water space the plate projects above the top and below the bottom of the water distributor 9 as indicated by the reference numerals 25^a in Figs. 2 and 17^a.

26, Figs. 1, 2 and 3 are water tubes situated below the usual fire arch in the fire-box these tubes being expanded at their opposite ends in holes respectively in the plate 5 at the rear end of the fire-box and in the inner plate 5^a at the front end of the fire-box. These tubes 26 provide for circulation of water between the water spaces at the back and front of the fire-box.

27, 27^a (Figs. 1, 2, 18, 19, 21 and 22) are longitudinal boiler stays, the stays 27^a extending through the water collector or water receiving drum 8 preferably close to the wall thereof, as shown in Fig. 2, the said stays being secured in place at the ends of the fire-box preferably by removable pins 28.

35 In the spaces between the side plates 6 of the fire-box and the down take water tubes 12 and water distributors 9 suitable heat insulating lagging is provided, 29 (Figs. 2 and 22) being angle plates confining this lagging at the top of the said spaces.

Similar lagging may be provided between the wrapper plates 16 and the inwardly bent upper portions of the up-flow or up-take water tubes 13.

It will be understood that water from the water space in the barrel or body of the boiler flows into the water distributors 9 and therefrom down the outer rows of downflow tubes 12 into the headers or junction boxes 11 and thence through the uptake or upflow tubes 13 into the aforesaid collector or water receiving drum 8, and that owing to the intense heat to which the tubes 13 are subjected in the fire-box, and to the weight of the large volume of cooler water descending the outer rows of tubes 12, the circulation of the water is very rapid, and liability of burning out of the tubes 13 and of lodgment of scale therein is minimized or prevented so that after prolonged use the tubes retain their original high efficiency for steam generation.

65 Further it will be understood that the hereinbefore mentioned water distributors

9 constitute feeders for the down-take or down-flow tubes 12, and that the hereinbefore mentioned headers constitute junction boxes for the lower or outlet ends of the said tubes 12 and the lower or inlet ends 70 of the up-take or up-flow tubes 13.

What we claim is:—

1. In a steam generator, a fire-box casing, fire-box end plates secured to the top and sides of the fire-box casing and forming front and rear spaces therein for steam and water, a receiving drum having its ends secured to the fire-box end plates and communicating with the said front and rear spaces, headers arranged longitudinally at the lower part of the sides of the fire-box and its casing, a series of inner water tubes connecting the said headers with the said receiving drum and forming with the latter the sides and top of the fire-box, water distributors arranged in the spaces between the fire-box and its casing and having their ends secured to the fire-box end plates and communicating with the said front and rear spaces independently of the receiving drum and of each other, and a series of outer water tubes connecting the said water distributors and headers and arranged in the spaces between the sides of the fire-box and the sides of the fire-box casing. 95

2. A steam generator as set forth in claim 1, the said water distributors being oblong in cross-section and arranged vertically in the spaces between the sides of the fire-box and the sides of the fire-box casing below the level of the bottom of the said receiving drum. 100

3. A steam generator as set forth in claim 1, and having also crown plates arranged above the upper end portions of the said inner tubes between the receiving drum and the water distributors and operating to prevent leakage from the fire-box casing into the fire-box between the tubes at its top. 105

4. A steam generator as set forth in claim 1, the said water distributors being spaced apart from the sides of the fire-box casing, and plates for supporting heat-insulating lagging secured between the adjacent sides of the said water distributors and casing in the upper parts of the spaces between them. 110

5. In a steam generator, a boiler barrel, a fire-box casing secured to and communicating with the boiler barrel, fire-box end plates secured in the front and rear end portions of the fire-box casing and forming water spaces therein, tubular water distributors having their end portions secured directly to the fire-box end plates and arranged longitudinally between the sides of the fire box and the sides of the fire-box casing and communicating with the water spaces at their ends, a receiving drum arranged longitudinally in the fire-box casing above and between the water distributors and com- 120 125 130

5 municating with the upper part of the space in the boiler shell, headers arranged longitudinally below the water distributors, a series of outer water tubes connecting the 10 water distributors with the headers at each side of the fire-box casing, and a series of inner water tubes connecting the headers with the said receiving drum, the said end plates, inner tubes and receiving drum forming the fire-box inside the fire-box casing.

6. In a steam generator, a fire-box casing, fire-box end plates secured in the fire-box casing and forming with it parts of a space which is a portion of the steam and water 15 space of the generator, a receiving drum having its ends secured to the fire-box end plates and communicating with the said space, a header arranged longitudinally at the lower part of the sides of the fire-box 20 and its casing, a series of inner water tubes connecting the said header with the said receiving drum and forming with the latter

one side of the fire-box and a portion of its top, a water distributor supported in the said space between the fire-box and its casing and communicating with the said space independently of the receiving drum, and a series of outer water tubes connecting the 25 said water distributor and header and also arranged in the said space between the sides 30 of the fire-box and its casing.

7. A steam generator as set forth in claim 5 and having also stiffening plates U-shaped in cross-section said plates being secured with their closed ends against the rear end 35 plate of the fire-box casing with their free end portions arranged vertically and projecting within the rear end portions of the said water distributors.

In testimony whereof we affix our signatures. 40
